UNITED STATES PATENT OFFICE.

HENRY G. LYKKEN, OF MINNEAPOLIS, MINNESOTA.

MEANS FOR TREATING MATERIALS.

Application filed July 12, 1923. Serial No. 651,020.

This invention relates to means for drying materials and comprises among its objects to improve upon present means for drying objects, such as coal and other fuels; 5 to provide an improved drying means, wherein hot air or gases which have heretofore been wasted are utilized for the drying of objects; to provide a new type of apparatus for the utilization of hot air or other 10 gases in the drying of materials which may need to be so treated; to provide apparatus in which materials may be dried and conditioned; to provide an apparatus of the character indicated in which the distribution of 15 the drying and cooling gases may be properly controlled; and such further objects, advantages, and capabilities as will later more fully appear and as are inherently possessed by the invention.

20 My invention further resides in the combination, construction, and arrangement of parts illustrated in the accompanying drawing and, while I have shown therein a preferred embodiment, I desire it understood 25 that this is illustrative only and not to be construed as a limitation of my invention.

Referring more in detail to the drawing annexed hereto and forming a part hereof, Fig. 1 is a diagrammatic plan view of a construction illustrating my invention; Fig. 2 is a section, more or less diagrammatic, of the construction shown in Fig. 1; Fig. 3 is a transverse section of the construction shown in Figs. 1 and 2; and Fig. 4 is a 35 broken side view of the conveyor and heating or cooling chambers.

In detail, numeral 1 designates suitable apparatus, such as a fan blower, for feeding cold air to a duct section 3, while numeral 2 40 designates a similar apparatus for feeding hot air or other gases to a duct section 4, these two sections forming one continuous duct divided by a movable partition 5 which may be inserted at any convenient place so as to vary the relative lengths of the two 45 duct sections 3 and 4. The hot gas is supplied to the force feeding means 2 in any suitable manner, such as by a duct 6 leading from a source of hot air or other gases.

50 Upon opposite sides of the duct sections 3 and 4 are arranged channels, through which run endless conveyors 9 and 10, with upper and lower runs, such that the upper runs of said conveyors carry the materials 55 to be dried, from the hoppers 11 and 12. By this means, the material being dried may

be carried forwardly, progressively, from the receiving means 11 and 12 and deposited at 13 and 14 in a dried condition, having, during its progress, passed over a series of 60 compartments 15 and 16, the former being supplied with a hot gas through the duct section 4 and the latter with cold air through the duct section 3. Gates 18 located in the sections 3 and 4 may be adjusted to regulate 65 the amount of air or other gas admitted to the compartments 15 and 16, through the port 15' at intervals in the sidewalls 3' of the duct sections 3 and 4. The series of 70 chambers 15 and 16 have outer side walls 75 19 between which and the side walls 3' operate the endless conveyors and between which are also located transverse walls 7 and 8, preferably of sheet metal, having laterally bent top flanges 20. The flanges 20 are located as near as possible to the bottom of the upper run of the conveyor so as to tolerably shut off flow of heating or cooling medium from one chamber or compartment to an adjacent chamber or compartment. 80 The ends of the walls 7 and 8 may be respectively secured in any suitable manner to the side walls 19 and 3', as by angle bars or irons 21 arranged substantially vertically as shown in the figures of the drawings. The lower end 22 of each wall 7 and 8 terminate above the lower or return run of the conveyor. To the side walls 19 and 3' are also secured tracks 23, 24, 25 and 26 running longitudinally of said walls 3' and 90 19 and upon which ride or run the side chains or rollers 27 and 28 of the side chains. Material 29 is supported upon the upper run of the conveyor and has lateral side guards 30 and 31 secured to the side walls 95 3' and 19. The side walls 19 may have angle pieces 32 to support the same on the foundation 33. Above the upper runs of the conveyors are arranged stirring elements or ploughs 17 supported from rods 34 adjustably connected, as by nuts 34' to cross bars 35 fastened at their ends by angle pieces 36 and 37 to the side walls 3' and 19 extended. As the material is carried against the ploughs 17 it will be turned over to expose new surfaces and be thoroughly stirred. Assuming 100 that the fuel has been sufficiently dried in its passage over the compartments 7 and 8 by the time it reaches the partition 5, this fuel then continues its course over other similar compartments through which cold air is forced, and the cooling process is then car- 110

ried out, so that by the time the fuel reaches the end of the conveyors, it will have been cooled sufficiently. Having reached the ends of the conveyors 9 and 10, the fuel is removed in any desired manner from 13 and 14. It will be understood that the heating and cooling media pass from the duct sections 3 and 4 through ports 15' into chambers or compartments 15 and 16 and upwardly through the upper runs of the conveyors and through the material carried thereby. The conveyors are of such construction as to readily hold the material for treatment without danger of the material falling through the conveyor, and to permit the upward passage of the heating or cooling media through the conveyors and the materials thereupon.

It will be understood, of course, that the hot air or other gases supplied to the duct 24 may be produced in any desired manner, it being most economical to use waste heat from some other operation, but, if desired, the heat can be furnished from a heater operated for the purpose of furnishing the same. Also, it will be understood that the thickness of the material on the moving conveyor may be adjusted and regulated as desired, the same being preferably done where the material issues from the hoppers 11 and 30 12. The dryer may be built in any desired number of units, made of any desired widths and lengths to suit the material being dried and may contain any desired number of compartments 7 and 8, the air or other gas being supplied to any desired number of these compartments to attain the desired results.

While I have illustrated and described herein a more or less specific embodiment of my invention, I desire the same to be understood as illustrative only and not as limiting said invention.

Having now described my invention, I claim:

1. A material treating device comprising a porous conveyor by which material to be treated may be carried, means for causing a passage of a treating medium through said conveyor and the material thereon, said means comprising a series of chambers located below said conveyor and being provided with open tops for the upward passage of the medium from each of said chambers to and through said conveyor and the material carried thereby, and a supply duct adjacent said chambers and having ports laterally communicating with said chambers for the passage of said medium through said ports from said duct to said chambers, and means for regulating the rate of passage of said medium through said ports.

2. A material treating device comprising a porous conveyor by which material to be treated may be carried, means for causing a passage of a treating medium through said conveyor and the material thereon, said means comprising a series of chambers located below said conveyor and being provided

ed with open tops for the upward passage of the medium from each of said chambers to and through said conveyor and the material carried thereby, a supply duct adjacent said chambers and having ports laterally communicating with said chambers for the passage of said medium through said ports from said duct to said chambers, and means for regulating the rate of passage of said medium through said ports.

3. A material treating device comprising a porous conveyor by which material to be treated may be carried, means for causing a passage of a treating medium through said conveyor and the material thereon, said means comprising a series of chambers located below said conveyor and being provided with open tops for the upward passage of the medium from each of said chambers to and through said conveyor and the material carried thereby, a supply duct adjacent said chambers and having ports laterally communicating with said chambers for the passage of said medium through said ports from said duct to said chambers, and means for dividing said ducts into sections whereby a medium of one kind may be supplied in one of said sections for passage to the chambers in communication with said section of said duct and a medium of another kind may be supplied in another of said sections for passage to the chambers in communication with said last mentioned section.

4. A material treating device comprising a porous conveyor by which material to be treated may be carried, means for causing a passage of a treating medium through said conveyor and the material thereon, said means comprising a series of chambers located below said conveyor and being provided with open tops for the upward passage of the medium from each of said chambers to and through said conveyor and the material carried thereby, a supply duct adjacent said chambers and having ports laterally communicating with said chambers for the passage of said medium through said ports from said duct to said chambers, means for dividing said duct into sections whereby a medium of one kind may be supplied in one of said sections for passage to the chambers in communication with said section of said duct, and a medium of another kind may be supplied in another of said sections for passage to the chambers in communication with said last mentioned section, and means for regulating the rate of passage of said medium through said ports.

5. A material treating device comprising a porous conveyor by which material to be treated may be carried, means for causing a passage of a treating medium through said conveyor and the material thereon, said means comprising a series of chambers located below said conveyor and being provided

- vided with open tops for the upward passage of the medium from each of said chambers to and through said conveyor and the material carried thereby, a supply duct adjacent said chambers and having ports laterally communicating with said chambers for the passage of said medium through said ports from said duct to said chambers, and mixing elements located above said conveyor and in the path of said material whereby the latter may be carried thereagainst and be stirred and mixed. 25
- 5 6. A material treating device, comprising a medium supply duct, a series of chambers located on each side of said duct, said duct having openings into said chambers, said chambers being open at the tops thereof, and a conveyor passing over the tops of said chambers in each of said series of chambers. 30
- 10 7. A material treating device, comprising a medium supply duct, a series of chambers located on each side of said duct, said duct having openings into said chambers, said chambers being open at the tops thereof, a 35
- 15 conveyor passing over the tops of said chambers in each of said series of chambers, and control gates at each of said openings between said duct and said chambers for regulating the passage of the medium from said duct to said chambers. 40
- 20 8. A material treating device, comprising a medium supply duct, a series of chambers located on each side of said duct, said duct having openings into said chambers, said chamber being open at the tops thereof, a 45
- 25 conveyor passing over the tops of said chambers in each of said series of chambers, a blower at each end of said duct, and means for selectively dividing said duct into sections whereby the blower at one end of the duct may supply one kind of medium to one of said sections and the blower at the other end of said duct may supply another kind of medium to another of said sections. 50
- 30 In witness whereof, I hereunto subscribe my name to this specification. 55
- 35 HENRY G. LYKKEN.
